UNITED STATES PATENT OFFICE.

ABIGAIL A. DRAPER, OF BLUE ISLAND, ILLINOIS.

DESIGN FOR A LABEL.

SPECIFICATION forming part of Design No. 19,368, dated October 22, 1889.

Application filed August 29, 1889. Serial No. 322,375. Term of patent 3½ years.

To all whom it may concern:

Be it known that I, ABIGAIL A. DRAPER, a citizen of the United States, residing at Blue Island, in the county of Cook and State of Illinois, have invented and produced a new and original Design for a Label for Bottles, of which the following is a specification, reference being had to the accompanying drawing, forming a part thereof.

10 The figure is a face view of my design for a label.

15 The leading feature of my design consists in the representation of a shield A, with a broad border C, of a dark color, around it, and the space within the border has a representa-

tion thereon of trees B and a lion D, and above the shield is the representation of a crown E.

I claim--

A design for a label for bottles shown and described, the same consisting of the representation of a shield having a broad dark border, and within the border having the representation of trees and a lion, and above the shield the representation of a crown. 20

ABIGAIL A. DRAPER.
